UNITED STATES PATENT OFFICE.

ALBERT J. LINDEMANN, OF MILWAUKEE, WISCONSIN, ASSIGNEE TO A. J. LINDEMANN
& HOVERSON CO., OF MILWAUKEE, WISCONSIN.

RESERVOIR FOR OIL-STOVES.

1,120,827.

Specification of Letters Patent. Patented Dec. 15, 1914.

Application filed August 14, 1914. Serial No. 856,722.

To all whom it may concern:

Be it known that I, ALBERT J. LINDEMANN, a citizen of the United States, and resident of Milwaukee, in the county of Milwaukee and State of Wisconsin, have invented certain new and useful Improvements in Reservoirs for Oil-Stoves; and I do hereby declare that the following is a full, clear, and exact description thereof.

10 My invention refers to oil burning stoves and has for its primary object to provide a simple, economical and effective means in connection with the stove for independently supporting a detachable main reservoir or 15 font over a supplemental reservoir, which supplemental reservoir is in pipe connection with the burner or burners.

Specific objects of my invention are to provide a main reservoir having a support 20 engaging shoulder or bead projecting from its body, the said reservoir being preferably composed of vitreous material, whereby its contents are visible. To provide a supporting hanger in connection with the stove for 25 engagement with the reservoir shoulder or bead and so constructed and arranged as to support said main reservoir over the auxiliary reservoir, whereby load strain is entirely relieved from the auxiliary reservoir, 30 while at the same time the said auxiliary reservoir is positioned to receive oil supply from the main reservoir. By this independent suspension of the main reservoir an air space between the reservoirs is maintained 35 forming a vent for the superimposed auxiliary reservoir. To provide the auxiliary reservoir with a collecting lip about its mouth, whereby drainage from the standard valve-controlled nozzle of the main reservoir is trapped and shed into said auxiliary 40 reservoir.

With the above and other objects in view the invention consists in certain peculiarities of construction and combination of parts as 45 fully set forth hereinafter with reference to the accompanying drawings and subsequently claimed.

In the drawings Figure 1 represents a fragmentary elevation of an oil burning stove equipped with a reservoir suspension means embodying the features of my invention, parts being broken away and in section to more clearly illustrate the details of construction; Fig. 2, a sectional plan view of the reservoir suspension mechanism, the

section being indicated by line 2—2 of Fig. 1; Fig. 3, a detailed partly sectional elevation of another form of reservoir suspension means embodying the features of my invention, and Fig. 4, a sectional plan view of the same, the section being indicated by line 4—4 of Fig. 3.

Referring by characters to the drawings, 1 represents an oil burning stove provided with a wick burner 2, which burner is supported by and in communication with an oil supply pipe 3. The oil supply pipe extends through an end wall 1' of the stove, its outer end being in threaded union with a bottom aperture of a horizontally disposed auxiliary reservoir 4. Thus it will be seen that the auxiliary reservoir is supported by its pipe connection to the burner, although, if desired, the said auxiliary reservoir may be otherwise braced.

As shown, the mouth of the auxiliary reservoir 4 is provided with an inwardly extended collecting lip 5, which lip is also inclined downwardly to form a catch basin, whereby drippings from the nozzle 7 of a main reservoir 8 are trapped and collected in the bottom of the auxiliary reservoir, it being understood that in seating the main reservoir in its position over the auxiliary reservoir, there is a liability for a slight leakage. The main reservoir is detachably supported by a hanger 9 that is secured to the side wall 1' of the stove. The hanger, in this exemplification of my invention, comprises a supporting ring 10 that forms a reservoir receiving aperture and the ring is provided with feet 10' that extend therefrom, having ends riveted or otherwise secured to the end wall 1' or frame of the stove.

The body of the main reservoir 8 is provided with suspension means projecting therefrom, in the form of a bead 8', which bead engages the ring when the reservoir is dropped into place and thus holds said reservoir in suspension whereby the weight of the same is supported independently of the auxiliary reservoir. As shown, the body of the reservoir is positioned vertically and the body bead is preferably located upon a plane above the center of said body. Thus the preponderance of the load is below the point of suspension, whereby tendency of the reservoir to tip is eliminated.

For convenience in fitting the main bot-

tle-like reservoir within the hanger ring the body of the same that merges into the shouldered nozzle portion 7 is slightly crowned or rounded, whereby the said reservoir will be, to a certain extent, self-centering when dropped into place. The nozzle 7 is equipped with a valve-controlling cap 11, the valve member being provided with a stem 12, which stem is adapted to engage 10 the bottom of the auxiliary reservoir when the main reservoir is in its position of rest. This valve stem engagement, which is for the purpose of opening the valve, is the only connection between the associated reservoirs.

The nozzle 7 extends through the mouth of the auxiliary reservoir but clears the edges thereof to form an air space between said mouth and the outer wall of 20 the nozzle, whereby the auxiliary reservoir is vented. Thus it will be seen that the main reservoir is detachably supported above the auxiliary reservoir and entirely independent of the same, so that load strain 25 upon said auxiliary reservoir is eliminated, while, at the same time the relative positions assumed by the reservoirs form an air space between the collecting lip 5 and the juxtaposed lower wall of the main reservoir. 30 This spacing of the reservoirs apart also effectually eliminates the tendency of oil being distributed about the body of the main reservoir by capillary attraction and hence the main reservoir is kept clean for convenience in handling.

While I have illustrated and described the skeleton hanger as an uninterrupted ring or band, it is obvious that the same may be varied within the knowledge of the ordinary 40 skill of the mechanic without departing from the spirit of my invention. It is also

noticeable that, in the several constructions shown, the skeleton or band-like hanger is designed to receive a main reservoir and support the same in such manner that said main reservoir is clearly visible both above and below the hanger, whereby its contents may be seen at a glance.

Figs. 3 and 4 of the drawings illustrate a modified form of hanger adapted to be stamped from a single piece of sheet metal. In this instance the sheet metal blank is stamped out to form a circular receiving aperture having a downturned flange 13, whereby the hanger is stiffened and the shank of the hanger is provided with feet 55 extensions 14 that serve as braces and also means for securing the said hanger to the frame or body of the stove 1'. It is manifest that the shelf-like hanger so formed of 60 pressed steel, may constitute a single stamping or the bracket portions may be attached thereto as a substitute for the integral feet.

I claim:

A stove having an oil burner, an auxiliary reservoir, and a pipe connecting the burner and reservoir; in combination with a skeleton hanger extending from the stove and over the auxiliary reservoir, and a main reservoir having a bead extending from its 70 body adapted to engage the hanger for supporting said main reservoir independent of the aforesaid auxiliary reservoir.

In testimony that I claim the foregoing I have hereunto set my hand at Milwaukee 75 in the county of Milwaukee and State of Wisconsin in the presence of two witnesses.

ALBERT J. LINDEMANN.
